UNITED STATES PATENT OFFICE.

PHILIP C. WENTWORTH, OF PROVIDENCE, RHODE ISLAND.

RING TRAVELER.

1,415,073.

Specification of Letters Patent.

Patented May 9, 1922.

Original application filed January 11, 1921, Serial No. 436,585. Divided and this application filed November 5, 1921. Serial No. 513,119.

To all whom it may concern:

Be it known that I, PHILIP C. WENTWORTH, a citizen of the United States, residing at Providence, county of Providence, 5 State of Rhode Island, have invented certain new and useful Improvements in Ring Travelers, of which the following is a specification.

This invention relates to ring travelers and 10 is a division of my pending application Serial No. 436,585, filed January 11, 1921, to which reference is made.

In the particular form of ring traveler involved in the present application, the bow 15 of the traveler is provided with a plurality of rectangular shaped spaced vent openings which permit a draft through the traveler effective to prevent the accumulation of lint on the traveler and to keep the inner or 20 contacting horn of the traveler cool.

The construction and operation of my traveler, together with a selected embodiment which well illustrates the principles involved, is described and illustrated in the 25 accompanying specification and drawings, and the characteristic features of novelty particularly pointed out in the appended claims.

Throughout the specification and drawings like reference characters are employed 30 to indicate corresponding parts, and in the drawings:

Figs. 1 and 2 are side and top views, respectively, of a traveler in accordance with 35 my invention.

Fig. 3 is a fragmentary view of a ring with traveler positioned thereon as in operation, and

Fig. 4 is a diagrammatic view illustrating 40 the position of the ring relative to the spindle.

My ring traveler is of standard type comprising a bow portion 1 and terminal horns 2.

The bow portion 1 is provided with one or 45 more rectangular shaped openings 3 therethrough which permit a draft directly into the traveler itself substantially transversely of the bow portion 1 thereby preventing the accumulation of lint on the traveler.

The draft through the openings 3 also 50 tends to cool the traveler, particularly at the inner or contacting horn which becomes heated by reason of its continuous contact with the ring. The effect of the heat is to draw the temper of the traveler and to 55 "burn" the ring.

As here shown the openings 3 are disposed as longitudinally extending slots separated by an intervening tongue or bar of metal 4 which is preferably slightly de- 60 pressed as appears in Fig. 1.

The ring is indicated diagrammatically in Figs. 3 and 4 at R, the spindle at S, the yarn at Y and the traveler at 1.

What I therefore desire to secure by Let- 65 ters Patent is:

1. A ring traveler comprising a body pro- 70 vided with a plurality of rectangular shaped openings therethrough.

2. A traveler comprising a body portion 70 having a pair of spaced slits therein and having the material of the traveler between said slits depressed.

3. A traveler comprising a body portion 75 having a pair of spaced longitudinally ex- 75 tendsing slits therein and having the ma- terial of the traveler between said slits de- pressed.

4. A ring traveler comprising a body pro- 80 vided with a pair of spaced longitudinally ex- 80 tendsing openings therethrough.

5. A ring traveler comprising a body pro- 85 vided with a pair of spaced longitudinally ex- 85 tendsing rectangularly shaped openings therethrough.

6. A ring traveler comprising a bow pro- 90 vided with a pair of spaced parallel rectan- 90 gularly shaped openings therethrough.

7. A ring traveler comprising a bow pro- 95 vided with a pair of spaced parallel longi- 95 tudinally extending rectangularly shaped openings therethrough.

In testimony whereof I affix my signature in presence of two witnesses.

PHILIP C. WENTWORTH.

Witnesses:

C. D. TAYLOR.
